UNITED STATES PATENT OFFICE.

AUSTIN E. COFRIN, OF GREEN BAY, WISCONSIN.

PAPER-MAKING MACHINE.

Application filed June 12, 1924. Serial No. 719,585.

This invention relates to paper making, and particularly to the handling of paper in paper making machines.

One of the main problems encountered in the making of paper is to keep the paper continuously running over the paper machine without adhering to and breaking on the press rolls used in connection with the paper carrying felts for pressing out moisture and getting the paper into as dry a state as possible. In some instances the film of paper is carried through the press rolls between two felts; in other cases it is carried through the press rolls on one felt only. In either case the web of paper must eventually be taken off the felt or felts and carried over the remainder of the machine to be wound on reels.

The customary way of accomplishing this removal of the web of paper from its carrying felt is to run both the felt and web of paper between two or more rollers, separating the paper web from the felt by leading them off in different directions after they have passed through the rollers. These rollers are arranged to exert pressure on the felt and web of paper for the purpose of effecting separation of the paper from the felt, in accordance with the fact that the web of paper has a tendency to adhere to the harder of two surfaces with which it is brought in contact, and the desired slightly increased adherence of the paper web to the metal roll aids in effecting its separation from the felt.

By this method of separating the paper from the felt, however, the difficulty is experienced that the paper has a tendency to adhere to the metal roll to such an extent that frequent breakage occurs in separating it therefrom, causing delays and decreased production.

Another method of separating the paper from the felt is to run the felt a considerable distance in a substantially horizontal plane, and attempt to lift the paper off the felt, passing it over a roller arranged more or less remote with respect to the felt. The paper, however, tends to adhere tightly to the felt, particularly as they have usually been previously pressed together in passing through the usual moisture expressing pressure rolls, and as a result of this adherence it is difficult to effect separation of the paper without breaking it.

It is, accordingly, an object of the present

invention to provide a means for separating the web of paper pulp from its carrying felt which will eliminate breakage of the paper and enable the machine to be run 60 without interruption.

Another object of the invention is to effect the separation of the web of paper from the felt without the adherence of the paper to the removing roll.

A further object of the invention is to provide a roller which, in the operation of the machine, will effect separation of the paper from the pick up felt without causing adherence of the paper web to the roller 70 and without causing breakage of the paper web.

Other objects and advantages of the invention will appear from the following description, taken in connection with the accompanying drawings, which illustrate, by way of example, a preferred embodiment thereof, and in which:

Fig. 1 is a diagrammatic side elevation of part of a paper making machine in which the present invention is embodied, showing the web of paper in its preferred initial position when the machine is first started in operation.

Fig. 2 is a diagrammatic side elevation of the same, showing the web of paper arranged in accordance with the present invention for continuous running through the machine after it has been started.

An illustration of the whole of a paper making machine not being necessary to the present invention, certain parts not pertinent thereto have been omitted in the interest of simplicity. The usual or any desired type of paper making machine may be used in connection with the invention, and to the left of Fig. 1 may be, for example, the usual Fourdrinier machine, wire, and a first set of press rolls between which pass the upper and lower wool felts carrying the web of 100 paper pulp. The web of paper is then transferred to the pick up felt 9, and is shown as being carried on the bottom of said felt, which is preferably of porous or fibrous material, though it could as well be 105 carried on the top thereof, and the arrangement of rolls altered accordingly.

In accordance with the present invention, when the machine is started in operation, the film of paper 10 follows the pick up 110 felt 9 successively over the felt carrying rolls 11 and 12 in the direction indicated by the

arrows, and both the felt and paper pass between the upper and lower press rolls 13 and 14, where the film of paper collects on the doctor 15.

5 A preferred embodiment of the invention is shown in the drawings, and consists of an outside rider roll 16, arranged against the felt 9. This roll may be arranged to rotate on a fixed axis, or may be mounted to be 10 adjusted toward or away from the felt 9. If desired, it may be mounted on a shaft urged toward the felt 9 by a spring, or may be otherwise yieldably mounted. In any case, the roll 16 is, in accordance with the 15 present invention, so arranged that it presses very lightly against the paper web, its pressure being sufficient to insure separation of the web from the felt, but not sufficient to cause the paper to adhere to the roll.

20 When the machine is started in operation, both paper web and felt ride past the roll 16, and, as described, pass between the press rolls 13 and 14.

To effect separation of the paper web 25 from the felt 9, for the purpose of passing the paper web through the remainder of the machine, and particularly over the dryer, the paper on the Fourdrinier wire is cut through, thus starting a new strip, which 30 travels with the pick up felt 9 until it reaches the rider roll 16. The paper web passes the rider roll 16 between it and the felt 9, and at this point it is detached from the pick up felt and is led over the roll 16, as 35 shown in Fig. 2, and through the remainder of the machine.

By way of illustration, it is shown as passing 40 over the paper carrying roll 17 to the dryer 18, around the dryer between it and the dryer felt 19, which travels over suitable 45 dryer felt rolls 20, 21, 22 and 23, the paper web being shown as then passing over the paper roll 24 to be ultimately wound on reels in the usual manner.

50 It is found that, although the roll 16, arranged as described against a sheet of paper which adheres to a pick up felt, does not of itself initially pick the paper off the pick up felt unless the end of the paper is led over the roll, yet it does, in operation, keep the paper sheet from adhering to the pick up felt after it passes the roller.

55 Where two pressure rolls are used for effecting separation of the paper from the felt, the paper is pressed not only into the felt, but also against the removing roll. Further, the roll on the felt side tends to prevent the entrance of air between the felt and the paper, and because of this vacuum 60 effect, and the increased pressure of the web of paper into the felt, and especially its pressure against the removing roll, the paper web adheres to this roll to such an extent that the force required to remove it 65 frequently causes it to break.

The single roll used in the present invention, on the other hand, exerts very slight pressure on the paper and felt, does not press the paper into the felt, and leaves one side of the felt completely clear for the entrance of 70 air between the porous felt and paper. Particularly, the felt and paper web are urged against this single roll only by the tension of the felt, with the result that the paper does not adhere to the roll, but comes off 75 the roll readily and without breakage.

Where two rolls are used, and it is desired to effect the separation of the paper from the felt in accordance with the present invention, they may be adjusted with respect 80 to each other so that the paper is not pressed against the removing roll with enough force to cause its adherence thereto.

What is claimed is:

1. In a paper making machine, a plurality 85 of spaced felt-carrying rolls, a pick-up felt trained about the rolls and carrying a moist web of paper pulp adhering thereto, and means for effecting separation of the web from the felt in the operation of the machine 90 comprising a single roller spaced from said felt-carrying rolls and bearing upon the web intermediate a pair thereof.

2. In a paper making machine, a plurality 95 of spaced felt-carrying rolls, a porous pick-up felt trained about the rolls and carrying a moist web of paper pulp adhering thereto, and means for effecting separation of the web from the felt in the operation of the machine 100 comprising a single roller spaced from said felt-carrying rolls and bearing upon the web intermediate a pair thereof.

3. In a paper making machine, a plurality 105 of spaced felt-carrying rolls, a pick-up felt trained about the rolls and carrying a moist web of paper pulp adhering thereto, and means for effecting separation of the web from the felt in the operation of the machine comprising a single roller spaced from said 110 felt-carrying rolls and exerting a pressure against the web and felt sufficient to effect removal of the web from the felt without causing adherence of the web to the roller.

4. In a paper making machine, a plurality 115 of spaced felt-carrying rolls, a pick-up felt trained about the rolls and carrying a moist web of paper pulp adhering thereto, and means for effecting separation of the web from the felt in the operation of the machine 120 comprising a single freely rotatable roller spaced from said felt-carrying rolls and bearing upon the web intermediate a pair thereof.

5. In a paper making machine, a plurality 125 of spaced felt-carrying rolls, a pick-up felt trained about the rolls and carrying a moist web of paper pulp adhering thereto, and means for effecting separation of the web from the felt in the operation of the machine 130 including a roller associated with the felt

- intermediate and in spaced relation to the web of paper adhering thereto, and means for effecting separation of said moist web from said felt intermediate two successive felt-carrying rolls comprising a rider roll 50 associated with said felt out of direct coacting relation with the rolls and acting against the tension of said felt intermediate said two successive felt-carrying rolls.
6. In a paper making machine, a plurality of spaced felt-carrying rolls, a pick-up felt trained about the rolls and carrying a moist 10 web of paper pulp adhering thereto, and means for effecting separation of the web from the felt comprising a pressure roller mounted in coacting relation to the felt and out of direct coacting relation with said 15 rolls.
7. In a paper making machine, a plurality of spaced felt-carrying rolls, a pick-up felt trained about the rolls and carrying a moist 20 web of paper pulp adhering thereto, and means for effecting separation of the web from the felt comprising a pressure-exerting device mounted in coacting relation to the felt and out of direct coacting relation with said rolls.
- 25 8. In a paper making machine, a plurality of spaced felt-carrying rolls, a pick-up felt trained about the rolls and carrying a moist web of paper pulp adhering thereto, and means for effecting separation of the web 30 from the felt comprising a pressure-exerting roller spaced from the felt-carrying rolls and contacting with the web to urge the web and felt against the tension of the felt.
- 35 9. In a paper making machine, a plurality of spaced felt-carrying rolls, a pick-up felt trained about the rolls and carrying a moist web of paper pulp adhering thereto, and means for effecting separation of the web 40 from the felt comprising a rider roll associated with the felt out of direct coacting relation with the rolls and exerting pressure against the tension of the felt intermediate the felt-carrying rolls.
- 45 10. In a paper making machine, a plurality of spaced felt-carrying rolls, a pick-up felt carried thereby and carrying a moist
11. In a paper making machine, a pick 55 up felt carrying a moist web of paper adhering thereto, and means for effecting separation of said moist web from said felt comprising a rider roll associated with said felt, and said felt being urged against said rider 60 roll only by its own tension.
12. In a paper making machine, a pick 65 up felt supporting a moist film of paper and to which the moist film has a normal tendency to adhere, and a pressure exerting device contacting with one side of said felt and normally exerting pressure thereagainst and constituting the sole means for effecting separation of said film from said felt.
13. In a paper making machine, a pick 70 up felt of porous material supporting a moist film of paper and to which the moist film has a normal tendency to adhere, and a pressure exerting device contacting with one side of said felt and normally exerting pressure 75 thereagainst and constituting the sole means for effecting separation of said film from said felt.
14. In a paper making machine, a pick 80 up felt of porous material supporting a moist film of paper and to which the moist film has a normal tendency to adhere, and a roll contacting with one side of said felt and normally exerting pressure thereagainst 85 and constituting the sole means for effecting separation of said film from said felt and adapted to develop a vacuum effect with respect to the film only on the roll side thereof.

In testimony whereof I affix my signature.

AUSTIN E. COFRIN.
